(57) **CLAIM**

I claim the ornamental design for a golf club head, as shown and described.

DESCRIPTION

FIG. 1 is a perspective view of the golf club head, as viewed from above, the front and one side, according to a first embodiment.

FIG. 2 is a front elevation view of a golf club head of FIG. 1.

FIG. 3 is a rear elevation view of the golf club head of FIG. 1.

FIG. 4 is a side elevation view of a toe side of the golf club head of FIG. 1.

FIG. 5 is a side elevation view of a heel side of the golf club head of FIG. 1.

FIG. 6 is a top plan view of the golf club head of FIG. 1.

FIG. 7 is a bottom plan view of the golf club head of FIG. 1.

FIG. 8 is a perspective view of the golf club head of FIG. 1, as viewed from below, the rear and one side.

FIG. 9 is a perspective view of a golf club head, as viewed from above, the front and one side, according to a second embodiment.

FIG. 10 is a front elevation view of a golf club head of FIG. 9.

FIG. 11 is a rear elevation view of the golf club head of FIG. 9.

FIG. 12 is a side elevation view of a toe side of the golf club head of FIG. 9.

FIG. 13 is a side elevation view of a heel side of the golf club head of FIG. 9.

FIG. 14 is a top plan view of the golf club head of FIG. 9.

FIG. 15 is a bottom plan view of the golf club head of FIG. 9; and,

FIG. 16 is a perspective view of the golf club head of FIG. 9, as viewed from below, the rear and one side.

The broken lines in the drawings are for purpose of illustrating environmental structure as well as portions of the design that form no part of the present claimed design. The dash-dot broken lines represent a boundary and form no part of the claimed design.

Adjacent portions of the head are stippled differently to illustrate and claim contrasting surfaces of different color.
